UNITED STATES PATENT OFFICE.

CHARLES A. ROEBER, OF WASHINGTON, DISTRICT OF COLUMBIA.

LAMP-BRACKET.

SPECIFICATION forming part of Letters Patent No. 395,000, dated December 25, 1888.

Application filed February 2, 1888. Serial No. 262,757. (No model.)

To all whom it may concern:

Be it known that I, CHARLES A. ROEBER, of Washington, in the District of Columbia, have invented certain new and useful Improvements in Lamp-Brackets, of which the following is a specification.

My invention relates to lamp-brackets designed for permanent attachment to pianos, organs, and like instruments; and the improvements consist in a novel construction and arrangement of its parts, whereby the bracket is adapted to be folded back out of the way for safety during transportation.

The device is illustrated in the annexed drawings, in which—

Figure 1 is a perspective view of an instrument furnished with the improved brackets; Figs. 2 to 7, inclusive, detail views of the several parts of which the bracket is composed.

Heretofore it has been customary either to provide pianos, organs, and similar instruments with fixed wooden lamp-brackets, or, more recently, to apply a common metal bracket thereto after purchase and delivery of the instrument. The wooden brackets are large, cumbersome, and unsightly, and materially increase the difficulty of properly packing or boxing the instrument, besides being liable to become loose and unsafe through the shrinking and swelling of the wood in varying weather. Metallic brackets applied after delivery of the instruments rarely suit the purpose, not being specially designed therefor, and one style or form being unsuitable for different styles of cases. Moreover, the case is liable to be more or less injured in applying the bracket thereto; but if this happen at the factory the injury may be quickly repaired.

The impracticability of properly boxing or packing an instrument with brackets of any kind fixed in proper position for use has deterred manufacturers generally from adopting them, and it is to avoid this difficulty that my invention is designed, which I do by the construction now explained.

A indicates a bracket-plate of any suitable design and provided with holes to receive screws or other fastenings, and B an arm provided at its inner end with a pintle, b, designed to enter an opening, a, in a projecting arm or lug, c, which sets out from the face of plate A, as seen in Fig. 6. The pintle b is of cylin-

drical form or may be slightly tapered, and the hole or opening a is made of a form and size to receive said pintle and to permit the same to turn freely therein, but without side play. The portion of the pintle which is within the lug or arm c when the parts are in place is formed with a series of shallow sockets or cavities, d, in its circumferential face to receive the end of a set-screw, C, which passes through a threaded hole in the arm or lug c. With this construction and arrangement the arm B may be swung horizontally about the axis of its pintle b to any desired position.

The outer or free end of arm B is provided in its upper face and in one or both its side faces with a threaded hole or socket, e, as shown in Figs. 3 and 7, to receive the threaded stem or stud f of a cup or disk, D, which forms a receptacle for the lamp E, the form of the cup being varied to suit the style of lamp intended to be used.

When the device is to be used, the cup D is applied to arm B in a horizontal position, as shown at the right-hand side of Fig. 1 and in Fig. 2; but when the instrument to which it is applied is to be boxed or crated for shipment the cup or disk D is unscrewed from the top of said arm and applied to the side thereof, as shown in Fig. 1, after which the arm B is swung back parallel with the end of the case of the instrument, in which position it is safe from injury.

To prevent any movement of the bracket during transportation, the set-screw C is turned down to bear firmly upon the pintle b, its point entering one of the sockets of said pintle, and thereby effectually preventing any accidental loosening or slipping of the pintle within arm or lug c. So, too, the set-screw prevents the lamp-bracket from being accidentally moved while in use and precludes the lifting of the pintle b from its socket.

To prevent injury or marring of the case of the instrument by reason of the cup D striking against it, whether applied to the top or to the side of arm B, the plate A is advisably made with a lateral extension, A', which may be made quite ornamental, and which covers that portion of the case against which the cup might otherwise strike.

It is apparent that instead of providing the

bracket-arm B with threaded holes or sockets and the cup or disk D with a stem to enter said sockets the arrangement may be directly reversed; or the disk might be secured in any 5 convenient manner that would permit it to be changed from a horizontal to a vertical position—as, for instance, by means of a swivel-joint and set-screw or through-pin. If the sockets or the stems be provided at both sides 10 of the free end of arm B, the same bracket may be used for either end of the instrument; but otherwise the brackets must be made for right and left ends, respectively.

Although I prefer to add the lateral extension A' to the plate A, I do not restrict my 15 claims to such construction.

When the instrument is to be shipped, the lamp-bracket is folded back against its end, as shown at the left hand in Fig. 1; but when 20 unboxed and set up the instrument is made completely ready for use by loosening the set-screw, swinging arm B forward, and changing cup D from a vertical to a horizontal position.

I am aware that a stool for stores and like 25 places has been supported by a standard resting upon the floor and connected by a rod or bar with a hinge-piece secured to the front of a counter, the top of the stool being removable from the standard and adapted to be 30 placed thereon in a horizontal or a vertical position, as desired. This construction I do not claim.

My bracket is especially designed for use 35 upon pianos, organs, and like instruments, and the primary object sought is to adapt it for application to such instruments at the factory in such manner that it may be compactly folded out of the way during transportation,

prevented from marring the casing of the instrument, and kept entirely free from danger 40 of breakage or injury itself. These objects I attain by the construction above set forth, but they cannot be attained by the structure above disclaimed.

Having thus described my invention, what I 45 claim is—

1. A lamp-bracket consisting of a plate for attachment to a wall or article of furniture, a bracket-arm connected with and supported solely by said plate, and a disk adjustable 50 upon said arm from a horizontal to a vertical position.

2. In combination with an attaching-plate provided with a vertical socket, a bracket-arm having a vertical pintle to enter said socket, 55 a cup or disk carried by said arm and adjustable at will to either a horizontal or a vertical position thereon, and a set-screw passing through the socket-piece and bearing against the pintle, whereby the cup or disk may be 60 folded and held flat against the wall or surface to which the bracket is applied.

3. In combination with plate A, having lateral extension A', adapted to serve as a shield for the wall or instrument, and lug or arm c, 65 bracket-arm B, provided with pintle b and with cup or disk D, and a set-screw, C, passing through lug or arm c and bearing against pintle b.

In witness whereof I hereunto set my hand 70 in the presence of two witnesses.

CHARLES A. ROEBER.
